UNITED STATES PATENT OFFICE.

WILLIAM SANDERSON, OF CONNEAUTVILLE, PENNSYLVANIA.

END-GATE FOR VEHICLES.

1,356,560.

Specification of Letters Patent. Patented Oct. 26, 1920.

Application filed November 6, 1918. Serial No. 261,387.

To all whom it may concern:

Be it known that I, WILLIAM SANDERSON, a citizen of the United States, and resident of Conneautville, in the county of Crawford and State of Pennsylvania, have invented a new and useful Improvement in End-Gates for Vehicles; and I do hereby declare the following to be a full, clear, and exact description thereof.

10 My invention relates to end gates for vehicles, its object being to provide an improved form of latch for connection between the body and the end gate, giving a positive hold and pivoting means, and yet one which 15 is cheap in construction and can provide for the quick opening of the end gate when desired.

To this end, the invention comprises the vehicle body and the end gate, one member 20 having eye-bolts and the other member having a sliding locking bar mounted thereon with one end in line with an eye-bolt and with the other end bent back on itself to enter the other eye-bolt, and means for sliding 25 the locking bar. It also embodies other improvements as hereinafter set forth.

In the accompanying drawings, Figure 1 is an end view of a vehicle body embodying the invention; Fig. 2 is a side view of the 30 rear end thereof; Fig. 3 is a horizontal section on the line 3, 3, Fig. 1; Fig. 4 is a view showing the freeing of the end gate to swing on its upper pivot; Figs. 5 and 6 are views showing the swinging of the end gate on the 35 lower pivot; and Fig. 7 is an end view showing the vehicle body with the locking bar mounted on the body instead of on the end gate. Fig. 8 is a horizontal sectional view through the body of Fig. 7, showing the gate 40 open hinging on the locking bar.

The vehicle body 1 illustrated is adapted for use upon an ordinary chassis, such as a power-driven car, and it has the end sill 2 and has at the rear upper end thereof suitable pivoting means, as at 3, for mounting one end of the end gate 4, the end gate being mounted to swing either from its upper or its lower edge, as desired. The drawing illustrates the means for mounting the upper 45 edge of the end gate, which is disclosed in application for patent filed by me, January 3rd, 1918, Serial No. 210,199, having the upper bearings 5 provided with the rearwardly opening sockets or seats 6 in which 50 the hinge rod 7 is seated, said hinge rod having the clevises 8 adapted to fit over the

bearings 5 and so lock the hinge rod to the bearing forming the upper pivot for the end gate.

The pivot rod 7 is illustrated as mounted 60 in the straps 9, 9^a and 9^b, which extend across the end gate body and terminate in the bearings 10, 11 and 12, respectively, and the end-sill 2 of the body carries eye-bolts 14 and 15, the lower bearings 10, 11 and 12 being shown as in alinement with said eye-bolts 14 and 15, when the end gate is closed. The eye-bolts are shown as passing through the end-sills and securely held thereto by nut and bolt connection. Mounted in the 70 bearings 10, 11 and 12 is the sliding locking bar 16 which has the main straight body portion 17 mounted in the bearings 10 and 11, while the other end of the sliding bar is bent outwardly, as at 18, and thence back on itself, as at 19, the bent-back portion being mounted in the bearing 12. Thus, the bar provides the two locking ends 20 and 21 upon the same bar which extend in the same direction, and in alinement with each other, 80 one end 20 being a simple extension of the main body portion of the bar and being adapted to enter the eye-bolt 14, while the other end 21 is in alinement therewith and extends in the same direction, and is adapted 85 to enter the eye-bolt 15, the sliding bar thus providing for the locking of the lower edge of the end gate to the vehicle body. The two locking ends 20 and 21 also form with the eye-bolts 14 and 15 the pivots or hinge pins 90 for the swinging of the end gate upon the body. To hold the locking bar always in locking position, I provide the spring 22 engaging, for example, with the bearing 11 and a pin 23 on the locking bar 16. To provide for the easy movement of the locking bar, I provide the elbow lever 24 pivoted on the end gate, as at 25, and having a loop 26 fitting around the locking bar.

When it is desired to open the lower edge 100 of the end gate, it is only necessary by means of the lever 25 to move the locking bar longitudinally when its locking ends 20 and 21 are free from the eye-bolts 14 and 15, leaving the end gate free to swing on its upper pivots. As it swings back again into place, the locking bar can be moved sufficiently to pass the eye-bolts and the spring will force each end of the locking bar into engagement with the eye-bolts, quickly locking 105 the end gate in place. When it is desired to swing out the upper part of the end 110

gate, the locking bar forms the pivot therefor, and it is only necessary to disengage the upper end and swing it out in which case the end gate pivots on the locking bar 5 and can be swung down into vertical position, as shown in Fig. 6.

- Where it is desired to mount the locking bar on the body portion, as shown in Figs. 7 and 8, the end gate 28 carries the eyes 29, 10 and the locking bar 16 is mounted in bearings on the end-sill and has its ends 31 engaging with the eyes of the end gate, the locking bar being bent back on itself to 15 form the two locking ends, and the bar is operated by means of an end lever 32 mounted on the vehicle body, and in this case the end gate will swing on the pivots thus provided by the eyes thereon, hinging on the end portions of the bent locking bar.
- 20 The invention provides a very simple, cheap and strong means for mounting the end gate on the door, providing for both its quick release and its pivoting and its quick replacement. It also permits the hinging of 25 the door so that it can be lowered to absolutely vertical position when open.

What I claim is:—

1. The combination of a vehicle body, an end gate mounted thereon, eyes carried by 30 one of the said members, guides carried by the other member and a rod having one end mounted in one of the said guides in line with one of the said eyes and having its other end bent out of line and thence back 35 on itself to extend in the same direction and received in a bearing in line with the other eye, a spring tending to keep the ends of

the said rod in said eyes, and a disengaging lever operatively connected to the said rod.

2. The combination of a vehicle body, an 40 end gate mounted thereon, eyes carried by one of the said members, a combined hinge and latch carried by the other member, the said hinge and latch comprising a longitudinally movable bar mounted in guides 45 and having one of its ends adapted to enter one of the said eyes and having its other end bent out of line and thence back on itself to extend in the same direction and adapted to enter the other eye, and a disengaging lever operably connected to the bent 50 portion of the said bar.

3. The combination of a vehicle body, an end gate mounted thereon, the said vehicle body having an end sill provided with eye-bolts and the said end gate being provided with transverse straps and having an upper pivotal connection mounted in the said straps, the said straps forming bearings at the lower edge of the said end gate, and a 60 bar slidably mounted in the said bearings and having one end thereof adapted to enter one of the said eye-bolts and the other end bent back on itself to extend in the same direction and adapted to enter the other 65 eye-bolt.

In testimony whereof, I, the said WILLIAM SANDERSON, have hereunto set my hand.

WILLIAM SANDERSON.
